UNITED STATES PATENT OFFICE

FLOYD S. HARTWELL, OF CLEVELAND, OHIO, ASSIGNOR TO KELLY REAMER COMPANY,
OF CLEVELAND, OHIO

BORING BAR

Application filed August 23, 1926. Serial No. 181,081.

This invention relates to boring bars and other rotary cutters.

Briefly stated, an important object is to provide a boring bar in which the arrangement of the blades and the holding and adjusting means therefor is such that a substantial reduction in the size of the opening or openings for the reception of these parts is made possible whereby the strength of the bar adjacent the cutting units thereof compares favorably with the strength of the bar elsewhere.

A further and equally important object is to provide a boring bar in which the assembly and maintenance of the cutting and adjusting devices is greatly simplified and cheapened.

Other objects and advantages will be apparent during the course of the following description.

In the accompanying drawings forming a part of this application and in which like numerals are employed to designate like parts throughout the same,

Figure 1 is a fragmentary side elevation of a boring bar constructed in accordance with the invention;

Figure 2 is a longitudinal sectional view through the same;

Figure 3 is a perspective of an adjusting and holding nut embodied in the invention;

Figure 4 is a sectional view taken on line 4-4 of Figure 2;

Figure 5 is an end elevation of a carrier embodied in the invention;

Figure 6 is a longitudinal sectional view through the carrier;

Figure 7 is a sectional view taken on line 7-7 of Figure 6;

Figure 8 is a group perspective of the carrier and associated elements.

In the drawings, wherein for the purpose of illustration is shown a preferred embodiment of the invention, the numeral 5 designates a bar which may, of course, be provided with a shank 6 of any conventional or special design and by which the bar may be attached to a machine.

The boring bar illustrated is especially adapted for car wheel work and is provided

with longitudinally spaced roughing, finishing and chamfering cutters. The chamfering cutter is designated by the numeral 7. The general arrangement of the cutters, as illustrated in Figure 1, is old and well known in the art and the invention forming the subject matter of this application is in the nature of a holding and adjusting device by which the roughing and finishing blades may be held in place. Of course, the invention is capable of expression in a boring bar having only one set of cutters.

Referring to Figure 2, it will be seen that blades 8 are positioned in the openings 9 extending entirely through the bar. The blades 8 may have their edges notched, as indicated at 10, for the reception of suitably stout radial lugs 11 on adjusting and holding sleeve nuts 12.

In carrying out the invention, the sleeve nuts 12 are oppositely threaded and are mounted on the oppositely threaded portions of an adjusting and holding screw 15, the terminals of which are reduced and are extended through holding plates 18. The holding plates may in turn be secured in the recessed ends of a rectangular carrier 20, as clearly suggested in Figures 2 and 8. The reduced end portions of the adjusting and holding screw 15 may be provided with hexagonal sockets for the reception of an Allen wrench. Of course, the reduced end portions of the screw 15 may be provided with screw driver grooves or other tool engaging means.

Referring now to Figures 6 and 8, it will be seen that the carrier 20 is provided with a longitudinal channel interrupted intermediate the ends thereof by an arcuate bridge 22 upon which the reduced intermediate portion 24 of the adjusting screw 15 rests. In other words, the reduced intermediate portion 24 of the screw 15 defines a pair of annular shoulders which, as clearly shown in Figure 2, are engaged with opposite sides of the arcuate bridge 22 so that endwise movement of the adjusting screw is positively prevented.

Particular attention is invited to the fact that the longitudinal channel in the carrier 20 describes more than a semi-circle and that

the flat, oppositely located side walls 26 of the carrier are engaged with the opposed edges of the radial lugs 11 to securely hold the sleeve nuts 12 against turning during the 5 adjustment of the screw 15 or at any other time. Also, the sleeve nuts 12 are of a cross-sectional diameter to snugly fit within the longitudinal channel in the carrier 12 so that once the nuts 12 are mounted on the screw 15 10 and received in the channel the same will not get out of place. This greatly simplifies and expedites the assembly of the bar.

The rear edge of each carrier is provided with a tapered transverse groove 30 adapted 15 to partially receive taper locking screws 33 by which the carrier and the blades or cutters associated therewith may be securely held in place after being adjusted.

In assembling the bar it is simply necessary to place the adjusting screw 15 in the 20 channel with the intermediate portion 24 of the same resting on the arcuate bridge 22. It is important to note that when the screw 15 is originally introduced into the channel 25 in the carrier it is not connected to and does not carry the sleeve nuts 12.

The sleeve nuts 12 are arranged on the ends 30 of the screw 15 subsequent to the introduction of the screw into the channel of the carrier. This is necessary because of the cross-sectional formation of the channel in the carrier. To move the sleeve nuts 12 to the desired places on the screws 15 it is merely necessary to turn the screw so as to move 35 the sleeve nuts inwardly toward each other. Of course, it is desirable to start the sleeve nuts 12 onto the screw 15 at exactly the same time; otherwise they would not occupy the same relative positions on the screw.

40 When the sleeve nuts have thus been applied to the screw 15, the end plates 18 are secured by screw bolts or other suitable fastening means to the ends of the carrier so as to brace the ends of the screw. The blades 8 are now 45 engaged with the radial lugs 11 and the parts thus assembled are introduced into the rather narrow opening 9 in the bar. Finally, the taper screws 33 are applied and tightened to firmly bind the blades and the holding 50 means therefor in place against the strain to which the same will be subjected. After the tightening of the taper screws 33, necessary adjustment of the bar to the desired cutting diameter may be easily made by turning 55 the screw 15 from either end thereof.

It will be seen that the holding and adjusting members are no wider than the width 60 of the blades 8 as shown in Figure 7 and that these parts are arranged directly behind the blades so that the cross-sectional area of the opening or openings 9, as the case may be, may be such that the strength of the bar at the cutters compares favorably with the strength 65 of the bar elsewhere.

65 To provide a bar which is not substantially

weakened at the cutters thereof is especially advantageous in a heavy duty boring bar of the type illustrated since the strain incident to the use of the roughing cutters must be borne by that part of the bar near the finishing cutters as well as other parts of the bar. In other words, the strain on that portion of the bar adjacent the finishing cutters is not materially less than the strain on the bar elsewhere. 70 75

Having thus described the invention, what is claimed:

1. A boring bar comprising a body having an opening of substantially the same width throughout, a cutter in said opening, a carrier within said opening and having a channel, the intermediate portion of which has a bridge, an adjusting screw having shoulders engaged with said bridge, nuts on said screw, and cutters having connection with said nuts, the carrier having a longitudinal groove the side walls of which are undercut, the nuts having enlarged body portions received in said groove whereby the undercut groove walls hold the nuts in place, lugs extending from the nuts to engage the cutter, said carrier being wholly at one side of the cutters, the latter having recesses to receive said lugs, the recesses being deeper than the projective length of the lugs, and means for wedging 85 said carrier against one edge of said cutters whereby to force the same against the opposite wall of said opening, said carrier having the side edges thereof bearing directly against said cutters. 90 95 100

2. A boring bar comprising a body having an opening of substantially the same width throughout, a cutter in said opening, a carrier in said opening and having a channel opening out through one side thereof and having a wall describing more than a semi-circle, an adjusting screw having oppositely threaded portions in said channel, nuts on said oppositely threaded portions and having sliding engagement with the channel wall 105 and being provided with lugs extending through said opening in the carrier, blades engaged by said lugs, said carrier being provided with a bridge extending across said channel and engaging said screw to hold the screw against endwise movement, end plates connected to said carrier and having openings receiving the end portions of said screw, wedge locking means for the carrier for holding it in said opening, and said locking means 110 acting through said carrier to engage said blades to lock the same in set position, said carrier having the side edges thereof bearing directly against said cutters. 115 120

3. A boring bar comprising a body having an opening, a carrier in said opening and having a channel opening out through one side thereof and having a wall describing more than a semi-circle, an adjusting screw having oppositely threaded portions in said 125 130

channel, nuts on said oppositely threaded portions and having sliding engagement with the channel wall and being provided with lugs extending through said channel in the carrier, blades engaged by said lugs, said carrier being provided with a bridge extending across said channel and engaging said screw to hold the screw against endwise movement, end plates connected to said carrier and having openings receiving the end portions of said screw, and locking means to hold said carrier in place, said carrier being located entirely at the edges of the blades and being of substantially the same width as the blades, said carrier having the side edges thereof bearing directly against said cutters.

In testimony whereof I affix my signature.
FLOYD S. HARTWELL.
